UNITED STATES PATENT OFFICE.

OSCAR BOLL, OF WEST HOBOKEN, NEW JERSEY.

FLASHING.

1,394,403.

Specification of Letters Patent. Patented Oct. 18, 1921.

Application filed December 1, 1920. Serial No. 427,571.

To all whom it may concern:

Be it known that I, OSCAR BOLL, a citizen of the United States, and a resident of West Hoboken, in the county of Hudson 5 and State of New Jersey, have invented a new and Improved Flashing, of which the following is a description.

My invention relates to flashings such as are employed on a building at the siding, or 10 on a roof, or at a window or door frame, or in connection with a chimney, or otherwise where flashings usually are employed.

More particularly, the invention is intended as an improvement of a flashing 15 forming the subject matter of an application filed February 17, 1920, Serial Number 359,273.

The general object of my invention is to promote facility in the proper installation 20 of a flashing and the securing of the same in position as well as to improve the flashing in various particulars and provide for ventilating the space beneath the flashing owing to the sweating of flashing at the interior 25 and to provide a flashing that will be effective for its purpose and one that may be wholly or partially removable in making repairs in the flashing or on the adjacent building parts.

Reference is to be had to the accompanying drawings forming a part of this specification, it being understood that the drawings are merely illustrative of practical examples of the invention.

Figure 1 is an edge view of the flashing applied to a building at the siding, parts of the building being in section;

Fig. 2 is a horizontal section on the line 2—2, Fig. 1;

Fig. 3 is a fragmentary perspective view 40 of a portion of a building with the flashing in the form shown in Figs. 1 and 2 applied thereto;

Fig. 4 is a longitudinal section of the flashing in another form and showing the same applied to a pitch roof at the rear, the section being indicated by the line 4—4, Fig. 5;

Fig. 5 is a cross section on the line 5—5, Fig. 4;

Fig. 6 is a perspective view showing the flashing in modified form applied to a chimney;

Fig. 7 is a side elevation of the flashing as shown in Fig. 6;

Fig. 8 is an enlarged vertical section on line 8—8, Fig. 6;

Fig. 9 is a vertical section on the line 9—9, Fig. 7;

Fig. 10 is an enlarged fragmentary perspective view of a portion of the flashing shown in Figs. 6 to 9.

Referring at first to the form of the invention as shown in Figs. 1 and 2, my improved flashing includes two mating elements, one, 10, here shown as of approximately Z-shape, 65 presenting edge portions in the form of flanges, the one flange 11 having considerable area and in this form of the invention being adapted to lie beneath the material to which the flashing is applied, as for example, an overlapping siding A adjacent to a vertical window frame part B. The outer flange 12 terminates in a curved edge 13 adapted to receive interiorly the corresponding turned over rounded tubular edge portion 14 of the second element, 15 which, in this instance, 70 is adapted to lie at the surface of the material. The intermediate web of the Z-shaped element 10 lies in the joint between the frame strip B and the siding A and the element 15 extends across the joint. The interlocking of the turned over flanges or 75 interlocking edge portions 13, 14 establishes a hinge connection between the elements 10 and 15 as indicated by the dotted line, Fig. 85 2. Also, the one member 14 may be entered in the other member 13 by a sliding movement and may be similarly withdrawn. In practice, the element 10 is applied and secured in position with the securing of the siding A and the second element 15 having 90 been engaged therewith and properly positioned may be secured by a nail C or other fastener.

The outer element of the flashing has 95 members 17 to conform it to the surface presented by the overlapping siding A. These members 17 are separate from the outer elements (15) in order that members 17 having a particular conformation to suit the job in hand may be provided, in said element 15. In the illustrated example the members 17 at the outer edge 18 and the outer flashing element 15 at its free edge portion 16 are given a reverse hook form to provide an 100 interlocking seam connection between the flashing element 15 and the members 17. The interlocking turned-over edge members 105

13, 14 are so shaped and proportioned that an air space is provided between the same communicating with the space between the cover 15 and the outer flange 12, and said 5 outer edge member 13 is formed with ventilating apertures 22 so that the sweating or moisture deposited within the flashing may be dissipated.

The form of the invention as shown in 10 Figs. 4 and 5 is adapted to a shingle roof or the like at the edge. In this case the approximately Z-shaped element 10^a corresponding generally with the element 10 lies on the surface of the roof while hingedly 15 connected element 15^a corresponding generally with the element 15 lies beneath the roof shingles. The hinged and sliding connections are established by the hinge members 13^a, 14^a so that after the element 15^a on the 20 frame is placed in position and the roof and shingles applied over the same, the element 10^a can be connected with the element 15^a and lowered onto the roof. In carrying out the invention as in Figs. 4 and 5 the outer 25 element 10^a has the member 17^a to conform to the profile of the roof instead of having the corresponding members 17 on the element 15 as in the first-described construction. The members 17^a are each formed with a 30 returned edge portion 18^a in hook form to make a seam connection with the reversely turned edge 16^a on the flange 11^a of element 10^a, said flange corresponding otherwise with the flange 11 and being suitably fastened as 35 by nails F. The element 15^a which slides beneath the shingles may be secured by nails D or otherwise. I prefer to secure the element 10^a by fasteners 19 rigidly attached to the element 15^a and rising therefrom, said 40 fasteners presenting a length to be passed through apertures 20 in the element 10^a and turned down at the outside as clearly shown in Fig. 5.

I have indicated nails D fastening the 45 element 15^a and nails E fastening the shingles A'.

In the form of the invention shown in 50 Figs. 6 to 10 which shows the flashing applied to a pitch roof and chimney, the elements 10^b and 15^b are provided, hingedly connected by turned-over edge portions 13^b, 14^b, one of said elements being adapted to enter the material of the chimney and the other adapted to lie at the outside. The element 15^b is made flat to lie in the cement joints F of the brick chimney G and in this 55 case the outer curved edge portion 13^b corresponding with the edges 13, 13^a is formed on said element 15^b while the inner interlocking curved edge portion 14^b is on the outer element 10^b which lies pendent from the element 15^b on the surface of the chimney at one side, the mating flashing elements 60 running in series in step form along those sides of the chimney corresponding with the

pitch of the roof. At their lower edges the material of the flashing elements 10^b is returned on itself at the inside as at 23 and again returned outwardly as at 24 parallel with the body of the element 10^b to thereby 70 form a channel receiving the upper edge of the sheathing H or other roofing material, the channel serving to hold the paper, tin, or other roofing material. At the lower side of the chimney on the pitch roof, the element 10^c corresponding generally with the element 10^b hangs pendent from an element 15^c entered in the lower cement joint of the chimney, the two elements extending substantially the full width of the chimney and 80 the lower edge of the element 10^c receiving the roofing material H', it being understood that said element 10^c has a channel formed by the described members 23, 24. To connect adjacent elements 10^b a lip or 85 tongue 25 on the side edge of one of said elements enters between the return portion 23 and the body of the other element. To connect adjacent elements 10^b, 10^c at a corner of the chimney, said element 10^b has at its 90 lower edge a lip or tongue 25^a bent approximately at right angles, to lie at the inner side of the element 10^c, between the body of the latter and the returned portion 23 thereof. 95

In all cases, the flashing elements 10 and 15; 10^a and 15^a; 10^b and 15^b; 10^c and 15^c are connected by the interlocking curved edges to have a sliding hinge connection permitting engagement to be effected between 100 the respective elements after the one has been applied to the building and securely fastened. Thus, convenience is promoted in applying one element of the flashing, and after the same has been placed and secured 105 to the siding, chimney, roofing material, sheathing, metal covering, or the like, the other sliding and hinged element of the flashing can then be readily placed and secured in position. 110

The elements 10^b at the lower returned edge thereof have cut-outs 10^d for drainage of moisture deposited at the interior of the flashing, there being similar cut-outs 10^e in the element 10^c. 115

I would state in conclusion that while the illustrated examples constitute practical embodiments of my invention, I do not limit myself strictly to the exact details, since manifestly the same can be considerably 120 varied without departure from the spirit of the invention as defined in the appended claims.

I do not claim herein generic features common to the present application and to my 125 application Number 359,273, the generic invention being claimed in my first filed application. The invention of the present application resides in the improved feature of the attachable members 17 or 17^a to con- 130

form the outer flashing element to the surface of the siding, roofing, or the like, in the ventilating means, and in the specific embodiments of the invention herein illustrated.

Having thus described my invention, I claim:

1. A flashing comprising an element adapted to be entered in the building structure, and a coacting element to lie at the outer surface of the building material, said elements presenting spaced turned-over interlocking edges having vent openings, the space between the turned over edges communicating with the interior of the flashing to ventilate the body of the flashing by said vent openings in the interlocking edges.

2. A flashing comprising an element adapted to be entered in the material of a building, and an outer element; together with means forming a hinged connection between said elements, there being vent openings at the hinge and communicating with the interior of the flashing to ventilate the latter.

3. A flashing including an element adapted to lie at the surface of the material to which the flashing is applied, a holding flashing element with which the first element is connected, and means on the first-men-

tioned element adapted to receive members to conform to the surface of the material to which the flashing is applied.

4. A flashing comprising an element adapted to lie on the surface of the material to which the flashing is applied, a second flashing element to which the first element is adapted to be secured, and separate members fitting the first element and adapted to conform to the surface of the material to which the flashing is applied, said members and said first-mentioned element having engaging means to engage the one with the other, so that said members of various forms may be applied to said first-mentioned element.

5. A flashing comprising an element adapted to be entered in the material of a building, and an element adapted to lie on the outer surface of the building, means detachably connecting said elements, and means on the outer element at the free edge thereof adapted to receive roofing; together with inner and outer elements at an angle to the first-mentioned elements, the second mentioned outer element being connected with the adjacent first-mentioned outer element, so that the respective elements lie at adjacent sides of the structure.

OSCAR BOLL.
